FIG. 1 is a medial front perspective view of a shoe upper showing my new design;

FIG. 2 is a lateral front perspective view thereof;

FIG. 3 is a lateral side view thereof;

FIG. 4 is a medial side view thereof;

FIG. 5 is a front view thereof;

FIG. 6 is a rear view thereof; and,

FIG. 7 is a top view thereof.

The broken line showing of the circular elements, the bottom edge of the shoe upper and the remainder of the shoe upper is for illustrative purposes only and form no part of the claimed design.
